United States Patent Office.

LUCIEN DE GOLIA, OF BATCHELLERVILLE, NEW YORK.

Letters Patent No. 68,174, dated August 27, 1867.

IMPROVED WASH-BOARD.

The Schedule referred to in these Letters Patent and making part of the same.

TO ALL WHOM IT MAY CONCERN:

Be it known that I, LUCIEN DE GOLIA, of Batchellerville, in Saratoga county, and State of New York, have invented a new and improved Wash-Board; and I do hereby declare that the following is a full, clear, and exact description thereof, which will enable others skilled in the art to make and use the same, reference being had to the accompanying drawings, forming part of this specification, in which—

Figure 1 represents a front view of my improved wash-board.

Figure 2 is a central section of the same, the plane of section being indicated by the line $z z$, fig. 1.

Similar letters of reference indicate corresponding parts.

This invention relates to a new wash-board, which is provided with two corrugated surfaces, the one being formed in wood, the other in zinc.

The object of the invention is to make one board answer all requirements—all kinds of garments to be washed and all notions about the best kind of wash-boards—so that if there are two kinds of persons in a house differing in opinion as to whether the metal or wooden wash-board is the best, my invention will satisfy both.

A represents the frame in which the wooden wash-board B, corrugated on one side and smooth or corrugated on the other side, is held. The upper end of this board is smooth on both sides, and is on each side provided with a recess, a , for the holding of soap. Over the smooth face of the board B, or over that face of the same which is not to be used for washing, is laid a corrugated zinc or other metal plate, C, which is held to the frame A in any suitable manner. Thus a wash-board having a wooden and a metallic corrugated surface is arranged so that either side may be used whenever desired.

I claim as new, and desire to secure by Letters Patent as a new article of manufacture—

A wash-board provided with a wooden and with a metallic corrugated surface, substantially as and for the purpose herein shown and described.

L. DE GOLIA.
